ELECTRICAL TREATMENT APPARATUS AND
METHOD OF CONTROL

Franklin Offner, Chicago, Ill.

Application November 27, 1941, Serial No. 420,730

7 Claims. (Cl. 128—421)

1

This invention relates to electrical treating apparatus wherein an electric current is caused to pass through a substance or object to be treated; and more particularly to means and method for determining and controlling the strength of the current passed through the substance. The invention is especially useful in connection with electrical therapy apparatus for subjecting patients to heavy electrical currents of controlled intensity and for the purpose of illustration will be particularly described with reference to such apparatus.

It has been found that the application of rather heavy currents through electrodes on the scalps of patients suffering from mental diseases is often effective in producing therapeutic results. Because of the large currents employed, it is extremely important that the strength of the current be exactly controlled. In the past such control has been handicapped by the inability of the operator to measure the effective resistance existing between the electrodes at the current intensity which is to be employed in the treatment. There has also been the difficulty that even though the resistance were known, it has been necessary to make calculations and adjustments to achieve the correct voltage to properly treat the patient.

One object of this invention is to accurately predetermine the effective resistance of the patient to the treatment current. Another object is to properly set the treatment voltage to achieve the desired current intensity without the need of calculations. Still another object of the invention is to reduce the effect of variability of resistance of the patient. A further object is the elimination of excess current surges which might be injurious to the patient. A still further object is the provision of a means for measuring small testing currents without a sensitive meter. Other objects of the invention will become apparent from the following description of the invention with reference to the accompanying drawings, in which:

Fig. 1 is a diagrammatic representation of the general principles of the invention;

Fig. 2 is a diagrammatic representation of a form of the invention in which the same type of current is used for testing and treating;

Fig. 3 is a diagrammatic representation of the 50 equivalent electrical characteristics of tissue; and

Fig. 4 is a schematic diagram of a complete instrument, embodying the principles of the invention.

2 A basic principle of the invention is illustrated in Fig. 1. Here the input power to the therapy instrument is taken from a power source at 1. The strength of the power applied to the instrument is controlled by an adjustable power control means 2. If the power taken is alternating current, as it will usually be, the adjustable means 2 may be, and preferably is, a variable autotransformer. The power from the autotransformer 2 is then applied to two power conversion devices 3 and 4. 3 supplies current used for testing the resistance existing between the treatment electrodes 5 and 6, and 4 supplies the treatment current to the same electrodes. A switch 7 is placed in the circuit between device 3 and the electrodes. When switch 7 is closed, the test current is applied to said electrodes and its amplitude is measured on meter 8. A switch 9 is placed in the circuit between device 4 and the electrodes. When switch 9 is closed, switch 7 having first been opened, the treatment current is applied to the electrodes, and its amplitude may be measured on meter 10.

The over-all resistance of the testing circuit 25 (excluding the patient) must be adjusted to equal the over-all resistance of the treatment circuit. This may be accomplished by suitable adjustments in resistances employed in connection with power conversion devices 3 and 4. 30 Then the strengths of the power emanating from 3 and 4 will each continually advance as the strength of the power applied by control device 2 increases. Thus, we may write for the current through the electrodes 5 and 6 when switch 7 is closed:

$$I_{Test} = \frac{E_{Test}}{R_{Test} + R_{Patient\ Test}}$$

I_{Test} is the test current as read on meter 8; E_{Test} is the voltage which would be generated 40 across 5 and 6 with no current flowing; R_{Test} is the over-all internal resistance of the testing circuit; and $R_{Patient\ Test}$ is the resistance introduced across the electrodes 5, 6 by, for example, the patient.

45 Similarly, when switch 9 is closed, the treatment current, as read on meter 10, will be given by

$$I_{Treat} = \frac{E_{Treat}}{R_{Treat} + R_{Patient\ Treat}}$$

where the symbols are as before except that they refer to the treatment circuit.

Now, as said above, R_{Test} having been adjusted to equal R_{Treat} , let it be assumed that $R_{Patient\ Test} = 55 R_{Patient\ Treat}$; that is, that the resistance the

patient presents to the testing current is the same as that presented to the treatment current. Then it is clear that if E_{Test} bears a constant functional relationship to E_{Treat} , I_{Test} will have the same functional relationship to I_{Treat} ; that is, the ratio of I_{Test} to I_{Treat} will equal the ratio of E_{Test} to E_{Treat} for all values of voltage and patient resistance.

It is convenient to make the relationship of E_{Test} to E_{Treat} as nearly linear as practicable; that is, so that the variation in the power supplied by control device 2 will vary both E_{Test} and E_{Treat} by the same ratio. In what follows it will be assumed that such a linear relation holds. A small deviation from linearity will, in general, give slight and insignificant changes in the results.

A simple illustration of the above principle is illustrated in Fig. 2. Here the power is derived from an alternating current supply, and a variable autotransformer is therefore used at 2. 3 and 4 are replaced by a tapped transformer 11. Here the treatment voltage is supplied by the full secondary of 11; that is, the voltage between points 12 and 13. The testing current, on the other hand, is supplied by the voltage between 12 and the secondary tap 14; thus supplying a smaller alternating current voltage for testing. Meter 8 is now an alternating current milliammeter 15; meter 16 in place of meter 10 is a similar meter, but of higher range. The switches 7 and 9 are replaced by a double throw switch 17. When this is thrown to contact 18, the testing circuit is connected to the electrodes 5 and 6 and when at 19, the treatment circuit is connected to the electrodes.

Adjustable resistors 20 and 21 are introduced respectively into the testing and treatment circuits. The relative values of these are adjusted so that the total internal resistance in the two circuits is as nearly identical as possible. These resistors also have another function; by introducing the resistor 21 into the treatment circuit, and having said resistor large as compared with the effective patient resistance which will be inserted between electrodes 5 and 6, the effect of small variations in said patient resistance is minimized.

Because of the linear relationship between the test and treat voltages, the treatment current will always bear the same relationship to the test current. The test current meter may, therefore, be calibrated not in terms of the actual test current flowing, but rather in terms of the treatment current which will flow. That is, it will be calibrated to read

$$\frac{E_{Treat}}{E_{Test}} \times I_{Test}$$

Then when the switch 17 is turned to point 18 for testing, the variable transformer 2 may be adjusted until meter 15 reads the desired value of treatment current. Throwing switch 17 to 19 then will apply this actual treatment current through the electrodes. Thus, it is seen that the voltage is adjusted to the proper value as would be determined by application of Ohm's law, but no actual calculation is necessary. This is taken care of automatically by the construction of the apparatus.

The use of the apparatus of Fig. 2 assumes that the resistance of the patient to the power line frequency is the same for the testing current as for the treatment current. It was, however, discovered early in the art of electric shock

treatment of mental diseases that the resistance measured with a low value of current was not the effective resistance during treatment. No explanation of this was given, and, in fact, the opinion of experts in the art was that it was impossible to predict the effective value of patient resistance to the treatment current. Applicant has, however, discovered a means for predicting the effective resistance of the patient to the treatment current before application of said current. This then allows the voltage to be set to the proper value to give the desired value of treatment current.

Applicant has discovered that the apparent change in the patient's resistance when the treatment voltage is applied apparently is due to the change in the polarizable nature of the tissues through which the current flows. Referring to Fig. 3, the normal tissue may be considered roughly equivalent to a condenser 22, shunted by a resistor 23, the whole being in series with another resistor 24. The two terminals 25 and 26 represent the points of application of the electrodes with which these electrical characteristics are measured. For low frequencies such as 60 cycles per second, and for low intensities of current, the effective reactance of 22 is large, as is the resistance 23, as compared with the resistance 24. Representative values would be 22 equals $\frac{1}{2}$ microfarad, or approximately 5200 ohms reactance. Resistance 23 equals approximately 1090 ohms. Resistance 24 equals approximately 120 ohms.

It will thus be seen that at frequencies of the order of 60 cycles, almost all the voltage drop is a result of the parallel combination of 22 and 23. However, when the intense treatment current is applied, this excites the tissue under the electrodes, and results in a substantially complete short circuit of condenser 22. This may be represented as resistor 23 falling to a very low value, approximately 80 ohms. Thus resistance 24 is most effective in limiting the value of the treatment current, while resistance 23 also has some effect.

Applicant has also discovered a method of predicting the change. This is accomplished by measuring the resistance not with the low frequency current to be used in treatment, but rather with a relatively high frequency current. If the frequency is high enough, it will evidently go through condenser 22 almost unimpeded, and the effective resistance measured would be that of resistor 24 alone. If a somewhat lower frequency is used, condenser 22 will still present some reactance, and the frequency may be adjusted so that the effective impedance is that presented during treatment; that is, the impedance of 22 and 23 in parallel should add approximately 80 ohms to the total impedance presented between terminals 25 and 26. This is accomplished by using a frequency of approximately 7000 cycles per second for the testing current. The frequency used is, however, not at all critical, especially in the circuit used in which a resistor is placed in series with the patient, similar to resistance 21 of Fig. 2. This is described in greater detail below.

This principle of using a high frequency current for testing the patient's resistance could be employed by using ordinary resistance measurements for determination of this high frequency resistance, subsequently adjusting the treatment voltage, as determined by application of Ohm's law. However, a more convenient method is the

application of a circuit similar to that of Fig. 1. To employ this principle with this circuit and thus eliminate the need of calculations, device 3 may consist of an oscillator generating the desired frequency for testing: as above stated, approximately 7000 cycles per second. The voltage supply of this oscillator is derived from voltage control device 2 so that voltage at the test frequency is proportional to the voltage supplied by 2. Device 4 may then be a transformer to change the power input voltage to the desired voltage. A meter capable of responding to high frequency test currents of small amplitude is used at 8, whereas an ordinary A.-C. ammeter or milliammeter may be used at 10. As described above, the internal resistance of the test and treat circuits must be adjusted to equality. This may be accomplished by having resistors in devices 3 and 4 for making such adjustment; this is explained in greater detail below. Meter 8 may again be calibrated to read the treatment current directly so that in use the electrodes 5 and 6 may be placed on the patient and control 2 adjusted so that with 7 closed 8 will read the desired treatment current. On opening 7 and closing 9, the treatment current will then flow through the patient.

The wiring diagram of a complete instrument employing the principles described above is shown in Fig. 4. This illustrates an instrument for providing known current of the power-line frequency, for known intervals of time through the patient. The power-line current, as for example 115 volts sixty cycle alternating current, is supplied at the terminals 27, 28. The control device 2 of Fig. 1 is here a variable autotransformer 29. This supplies a variable voltage to the primary 30 of transformer 31. The secondary 32 of this transformer supplies the power for the treatment of the patient. The power for the testing circuit is also derived from the secondary of this transformer. This is a somewhat different arrangement than that shown in Fig. 1, the power being taken from the secondary for the purposes of utilizing the electrical isolating properties of transformer 31. Following the path of the treatment current, it is seen that said current next flows through the contacts 33 of relay 34. This relay is connected to a timing circuit. The current thence flows through the coil 35 and contacts 78 of a magnetic overload relay; thence (when the treatment switch 36 is depressed to "in" position) through one set of contacts 36a, of double-pole-double-throw switch 36, thence through resistor 37; thence through alternating current milliammeter 38; thence through one set of contacts 39a, of the test switch 39, which will be in the "out" position; and thence to one treatment electrode 40. The return circuit is through "ground," passing from electrode 41 through ground to the lower side of the secondary 32 of transformer 31.

Overload relay having coil 35 and contacts 78 is designed so that if a current exceeding a predetermined amount flows through its coil, the magnetic pull developed is such as to open the contacts 78 and said relay contacts will not again be closed until they are manually reset. The construction of such a relay is well known in electrical technology. Varying portions of resistor 42 are shunted across coil 35 by means of switch 43; in this way varying quantities of current may be bypassed around the coil so that the relay will operate to open the circuit at various desired values: e. g., 300, 500 or 700 milliamperes.

A voltmeter 44 is connected to read the voltage existing across the treatment electrodes; it may be used to register the value of the applied potential.

5 A power supply unit 45 supplies direct current power for operation of the timer circuit and of the test meter circuit. It consists of transformer 46 having primary 47 connected across the power line, a center-tapped high voltage winding 48, 10 a rectifier filament winding 49, and a heater current winding 50 for operating the heaters of all other vacuum tubes in the apparatus. The rectifier 51 rectifies the high voltage and condenser 52 smooths the oscillations in this voltage. Resistor 53 which is shunted across the power supply allows the selection of proper voltages for a timer tube 54.

The operation of the timer is as follows: the coil 34 of the timer relay is in the plate circuit 20 of vacuum tube 54. The cathode circuit is returned to a point on resistor 53 sufficiently positive that no plate current normally flows through coil 34. Variable resistor 55 which is constructed of a switch selecting a number of fixed resistors, 25 is connected between the grid of 54 and ground, the latter being also the most negative point of power supply 45. When testing, switch 39 is pushed "in," and contact 39b connects condenser 56 to the positive side of power supply 30 45. When switch 39 is released, condenser 56 remains charged to this voltage. When treatment switch 36 is closed, condenser 56 is connected through contacts 36b to the grid of 54, bringing the latter to a positive potential, and allowing 35 plate current to flow through coil 34. This results in the contacts 33 closing, and thus closes the treatment circuit. Condenser 56 almost instantaneously discharges through the grid circuit of 54 to a point where its voltage is equal to 40 the cathode voltage of 54. It subsequently discharges more slowly through resistor 55, and eventually the grid potential of 54 becomes so low that the plate current is insufficient to energize the coil 34 and hold contacts 33 closed. They will 45 then open, terminating the flow of treatment current. It will be seen that a great range of times may be achieved by varying the resistance of 55.

It will also be seen that the opening of switch 36 will terminate the treatment in two manners: 50 first, by causing the timer relay to open, through the opening of contacts 36b; and secondly, by opening the treatment current directly, by the opening of the contacts of 36a. Thus, dual control is had over the flow of the treatment current, and if for any reason the timer did not terminate the treatment at the desired time, it may be immediately terminated by release of switch 36. This prevents an overly long treatment which might occur if, for example, the contacts of relay 33 should stick together.

55 Another safety feature is that when contacts 36a are in the "out" position, the output of the treatment circuit is short-circuited. If then for any reason the timer circuit should stay closed, without having the treatment switch pushed in, and autotransformer 29 should be advanced to the point where appreciable voltage is developed by transformer 31, a large current will flow through coil 35 of the overload relay, causing it to open the circuit. This then prevents the instrument from being used when the timer circuit is inoperative.

70 The testing circuit 57 consists of oscillator tube 58, transformer 59, which has a tapped primary 75 60, and secondary 61, a plate block condenser 62,

oscillatory circuit condenser 63, grid leak 64 and condenser 65 and shunt feed resistor 66. It will be seen that this is the familiar Hartley oscillator circuit, with the frequency approximately determined by the inductance of primary 60, and condenser 63. For the present purposes this is best adjusted to approximately 7000 cycles per second. The secondary 61 of the transformer 59 is loaded by means of resistance 67; the purpose of this is to make this circuit have an almost pure resistive impedance, so that the resistance of the test and treat circuits may be equalized, as mentioned previously. As the plate voltage of 58 is supplied through resistor 66 from the secondary 32 of treatment transformer 31, said plate voltage will be nearly proportional to said treatment voltage. Likewise, the voltage appearing at the terminals of secondary 61 will also be closely proportional to the voltage of said treatment transformer. Thus the linear relationship between testing voltage and treatment voltage is preserved, as required.

Resistance 68 is inserted in series with the testing voltage in order to make the resistance of the testing circuit equal to that of the treatment circuit. It thus is similar in function to resistance 37 of the treatment circuit and will usually be of almost the same magnitude. Resistance 68 performs another function: it provides a source of voltage drop proportional to the testing current. Said voltage drop is measured by a vacuum tube microammeter, to be described below, thus giving the magnitude of the testing current.

The path of the testing current is as follows: when switch 39 is depressed the testing voltage is induced in secondary 61 of transformer 59 by oscillator 57. The voltage developed across resistance 67 causes a current to flow through the contacts 39a of switch 39; thence to patient electrode 40, through the patient, through electrode 41, thence to ground; thence through resistance 68 and thence back to the secondary 61 of transformer 59.

The vacuum tube microammeter 69 consists of vacuum tube 70, a combination diode and triode. The bias voltage for said triode is furnished by cathode resistor 71, which is bypassed by condenser 72. The plate voltage for said triode is supplied through plate coupling resistor 73 from the positive side of power supply 45. It will be seen that the triode unit of 70 thus amplifies the voltage appearing across resistor 68, due to the passage of the current, and said amplified voltage appears across resistor 73. This voltage is coupled into the diode circuit by means of condenser 74. The diode circuit consists of fixed resistor 75 and variable resistor 76 in series with D. C. microammeter 77; all being across the cathode and diode plates of 70. The alternating current voltage induced in this circuit through condenser 74 causes a rectified current to flow through the diode circuit, giving a reading on microammeter 77 closely proportional to the amplitude of said alternating current. Vacuum tube microammeter 69 is calibrated so that its reading for a given testing current will correspond to the desired value of treatment current. This is accomplished in the following manner: electrodes 40 and 41 may be short-circuited, or a resistance of the order of magnitude of the patient's resistance may be placed between said electrodes. In either case, the testing switch 39a is momentarily depressed, in order to set the timer. Sufficient resistance is introduced by resistance 55 into the timer circuit so that the timer will remain

closed for a considerable length of time; for example, 10 seconds. Treatment switch 36 is now depressed causing treatment current to flow. Its magnitude is noted on milliammeter 38, and variable transformer 29 is advanced until this current is of some desired value; for example, 500 milliamperes. Test switch 39 is now depressed, and assuming that the scale of microammeter 77 has been calibrated to read the treatment current directly, resistance 76 is adjusted until microammeter 77 registers the same current as was registered on milliammeter 38. Now in use it is only necessary to first press the test switch 39; adjust transformer 29 until microammeter 77 reads the desired current; then depress switch 36, whereupon the desired treatment current will be given the patient. The length of the treatment is, of course, controlled by the timer; this is started when the treatment switch 36 is depressed, and interrupts the current after the interval pre-set by means of resistance 55.

Resistance 37, which is in the treatment circuit, is variable and is adjusted in the following manner: electrodes 40 and 41 are short-circuited, testing switch 39 depressed, and the variable transformer 29 adjusted so that some given reading is registered on microammeter 77. The treatment switch is now depressed, with testing switch having been released, and the treatment current read on milliammeter 38. The treat switch 36 is now released, and a resistance introduced between electrodes 40 and 41. This resistance may be of the order of magnitude of the patient's resistance. The above procedure is again carried out, the microammeter 77 being brought to the same reading as before by adjusting 29, and the reading of 38 is again noted. When the adjustment of resistance 37 is correct, this will be the same as before. If it reads more than before, this indicates that resistance 37 is of too high a value, and should be reduced; and vice-versa.

It will be seen that when testing switch 39 is depressed, the treatment circuit is interrupted by the opening of "out" contacts 39a. This prevents a simultaneous application of the testing and treatment currents, which might not only be injurious to the patient but to the instrument as well.

As before described, it is necessary to press the test switch 39 to charge the condenser 56 in order to make the timer operative. This thus insures that the test reading will be made before the treatment is given, and is a safety feature of the instrument.

In the specification, the principles of the invention have been described as applied to a medical therapeutic device, and it has been especially used in the production of convulsive shock in the treatment of mental disorders. It has been particularly useful in this field because of the very close control of the treatment current which it provides. However, these principles can be applied in other fields, and especially wherever it is necessary to set a current to the desired value before the application of the full strength of current; and also wherever the electrical characteristics of the medium through which the current is to be applied approaches those described above as being the characteristics of living tissue. The invention is, therefore, not limited to the particular uses and embodiments described for the purpose of illustration, but is of broad scope as defined by the following claims.

The term "circuit" as used herein is intended

to denote a conductive part or a system of conducting parts through which current is intended to flow.

I claim:

1. The method of preselecting the magnitude of a low frequency treatment current which comprises passing through a subject to be treated a test current having a frequency of the order of 7000 cycles, measuring the effective impedance of the subject to the test current and adjusting the test circuit and treatment circuit simultaneously and proportionately to a value of the test current having a predetermined relationship to the desired value of the treating current.

2. The method of preselecting the magnitude of a low frequency treatment current which comprises passing through a subject to be treated a test current having a frequency not materially less than about 7000 cycles, measuring the effective impedance of the subject to the test current and adjusting the test circuit and treatment circuit simultaneously and proportionately to a value of the test current having a predetermined relationship to the desired value of the treating current.

3. In electrical treatment apparatus, a low frequency current source, current supply adjusting means connected to said low frequency current source, current applying electrodes, means including a current measuring device and a timing means connecting said current supply adjusting means to said electrodes, means connected to said current supply adjusting means for converting the low frequency current to high frequency current, means including a second current measuring device for connecting said current converting means to said electrodes independently of the low frequency current connecting means, and variable impedance elements for calibrating said second current measuring device in terms of the low frequency current indication of said first current measuring device.

4. In an electrical treatment apparatus as defined in claim 3, means in one of said (low frequency and high frequency) current connecting means for adjustment of the internal impedance of said low frequency and high frequency current connecting means to the same value.

5. In an electrical treatment apparatus as defined in claim 3, an impedance in said low frequency current connecting means having a higher value than the value of the impedance of the subject under treatment, whereby the effect of

small changes in the resistance of the subject is decreased.

6. In an electrical treatment apparatus as defined in claim 3, said means for converting the low frequency current to high frequency current including a vacuum tube oscillator circuit.

7. In an electrical treatment apparatus as defined in claim 3, said second current measuring device including an impedance in said high frequency current connecting means, an electron tube amplifier for amplifying the voltage developed across said impedance, and means for measuring the intensity of said amplified voltage.

FRANKLIN OFFNER.
